END SHIELD FOR A DYNAMO-ELECTRIC MACHINE

Roger B. Kerr, Jamestown, R. I., assignor to General Elec-
tric Company, a corporation of New York

Original application February 23, 1954, Serial No.
D. 29,170. Divided and this application November 16,
1955, Serial No. 38,921

Term of patent 14 years

(Cl. D26—5)

Fig. 2.

Fig. 1.

Fig. 3.

Fig. 4.

Fig. 1 is an end view of an end shield for a dynamoelectric machine showing my new design;

Fig. 2 is a side elevational view thereof.

Fig. 3 is a bottom plan view thereof; and

Fig. 4 is a perspective view thereof.

This application is a division of my co-pending application Serial No. D-29,170, filed February 23, 1954, now abandoned.

I claim:

The ornamental design for an end shield for a dynamoelectric machine, as shown and described.
